Inventor

UNITED STATES PATENT OFFICE.

ERNEST H. LAYTON, OF LOS ANGELES, CALIFORNIA.

DISTRIBUTOR.

Application filed June 1, 1922. Serial No. 565,276.

To all whom it may concern:

Be it known that I, ERNEST H. LAYTON, a citizen of the United States, residing at Los Angeles, in the county of Los Angeles 5 and State of California, have invented a new and useful Distributor, of which the following is a specification.

This invention is adapted to various uses amongst which may be mentioned, advertising, games, shooting gallery practice, and field and home practice for training to shoot.

The invention is broadly new, basic and pioneer in that I have provided a projectile formed of a plaited sheet constituting an 15 elongate body, and a tip formed by the bend of a loop of material bent over the front end of said body and constituting means for holding the plaits together at said front end of the body so that the plaited sheet may 20 be projected through the air like a dart and distribution of the sheets may thus be effected with great ease and certainty; and by removing the plaited sheet from the tip, or vice versa, the sheet may be easily opened 25 out to expose any inscriptions thereon.

The means for holding the plaits together at one end of the body may consist of a fold 30 of material having sufficient set to hold the plaits and prevent them from spreading apart; while the plaits throughout the body are free to expand fan-shape. Such clip 35 may be of metal or any other suitable material. The projectile so formed, is particularly adapted to the distribution of advertising matter.

Heretofore, house to house distribution of advertising matter such as hand bills and dodgers has required the distributor to walk great distances and under such conditions 40 the capacity for properly distributing the hand bills from door to door is limited to about one thousand bills per day for an ordinary distributor, and as such distribution is usually paid for by the thousand and the 45 remuneration per thousand is usually low, it is hard to get conscientious distributors to work for the prices that can be profitable to the advertiser, and it is possible that the distributor may yield to the temptation of 50 disposing of dodgers or hand bills without actual distribution.

An object of this invention is to provide, for advertising purposes, a hand bill or dodger which may be cheaply and conveniently made and which can be distributed

by pneumatic pressure at a high rate of speed either by a pedestrian or by an operator riding in, and distributing from, an automobile.

An object is to make provision whereby 60 the distributor can accurately place the hand bill at individual doors distant from the street, and may also place the bills at doors and windows opening onto balconies, from bottom to top of a building; and 65 whereby the distributor in an automobile going at high speed can accurately place the advertisement in front of each door he passes on the side of the street on which he wishes to make the distribution. 70

By printing the advertisement on the bill and then creasing the bill into plaits, and then bending onto one end of the plaits a fold of sheet material such as brass, an advertising projectile adapted to accomplish 75 the purposes above indicated is produced.

An object of the invention is to make cheap, simple and convenient provision whereby the distributor may invariably place, singly, and at such places as he 80 wishes, advertisements that can be easily opened, and read by the one who picks them up from such place.

I have discovered that such projectiles can be accurately thrown by hand, and also that 85 it may be discharged from a tube by compressed air.

The invention includes the projectile and a tube constructed to discharge the projectile to effect the distribution. 90

An object and an advantage attained is security against displacement of the hand bill by the wind.

Other objects, advantages and features of 95 invention may appear from the accompanying drawing, the subjoined detail description and the appended claims.

The invention may be carried out in various ways.

The accompanying drawing illustrates the 100 invention as applied in a simple, satisfactory device.

Figure 1 is a view of a distributor comprising an advertising projectile constructed in accordance with this invention and inserted in a tube from which it may be blown by compressed air or other suitable medium, the tube is shown in section. 105

Fig. 2 is an enlarged end view of the same, from the left of Fig. 1. 110

Fig. 3 is a perspective view of the projectile shown in Fig. 1 as the same might appear in flight.

Fig. 4 is an enlarged fragmental longitudinal section of the projectile shown in Figs. 1, 2 and 3.

Fig. 5 is a view on a smaller scale of the projectile body before it is plaited, and while it is flat after advertising matter has been printed on it. Dotted lines indicate the lines upon which the sheet will be bent into plaits prior to being secured by the clip.

Fig. 6 is an enlarged perspective view of the clip before it has been applied to the projectile body.

The sheet 1 is folded in fan fashion at lines 2 to form a plaited elongate body 3, the plaits in said body are held together at one end 4 by a clip 5 preferably formed of a rectangular piece of sheet metal bent at the middle into U shape, and one end 4 of the sheet is inserted in the clip 5 and the limbs of the clip are then bent to clasp and hold the end 4, thus forming a projectile; the clip 5 serving as the point or head of said projectile while the free end 6 of the sheet 1 spreads out in fan-shape to serve as a feather. The projectile 3 is then inserted in a tube 7 which is rectangular in cross section and may be constructed either of metal or pasteboard tubing. The projectile may then be ejected from the tube 7 by pneumatic pressure applied against the end 6 of said projectile with a strong, short and sudden blast. This may be done by the breath of the distributor, or by any expansive medium as compressed air or by the exhaust from an automobile or by any other suitable means connected to deliver the blast to the tube behind the folds.

The tip may be of pasteboard, celluloid, sheet metal or any other suitable material. Sheet metal is preferred as it adds sufficient weight to the end of the plaited body to remain at one point around which the main body may spin in the wind without being blown away.

By enclosing the front ends of the plaits with a loop in which the end of the plaited body is inserted, the bend of the loop forms a round and smooth front tip adapted to allow each projectile to be easily separated from its fellows and to allow each to

be separately inserted with great ease into the projecting tube and to allow it to pass through the air with accurate flight and with minimized air resistance.

Attention is directed to the fact that the loop forming the tip, is smooth and without external projections. The object of this is to minimize air resistance and to facilitate the flight of the projectile, thus giving the projectile greater range and accuracy.

I claim—

1. A projectile composed of a plaited sheet forming an elongate body; and a U-shaped loop enclosing the front end of the plaited sheet; the bend of said loop forming the tip of the projectile; said loop constituting means for holding the plaits together at the front end of the body.

2. A tube rectangular in cross section and a fan-shaped projectile having a thin flat detachable, forwardly rounded tip forming the front end of the projectile, and adapted to be shot through said tube.

3. A tube rectangular in cross section and a projectile adapted to be pneumatically shot through said tube, said projectile consisting of a sheet plaited in fan-shape to form an elongate body and means to hold the plaits together at one end of said body while the rest of the body expands under the projecting blast to form a feather.

4. A projectile composed of a plaited sheet forming an elongate body; and a loop for holding the front end of the plaited sheet tightly folded together, said loop being free from external projections and forming the exterior of said front end.

5. A projectile composed of a plaited sheet adapted to fold into a body of rectangular cross section, and means to hold the tip of said body folded in such rectangular cross section, forming a smooth front end of said projectile to permit it to pass freely through the air, and allowing the body of the projectile to expand into fan-shape behind said front end.

In testimony whereof I have hereunto set my hand at Los Angeles, California, this 24th day of May 1922.

ERNEST H. LAYTON.
